UNITED STATES PATENT OFFICE.

CHARLES R. CRANE, 2d, OF CHICAGO, ILLINOIS, ASSIGNOR TO CRANE CO., OF CHICAGO, ILLINOIS, A CORPORATION OF ILLINOIS.

DESIGN FOR A FAUCET.

Application filed December 6, 1923. Serial No. 7,968. Term of patent 14 years.

To all whom it may concern:

Be it known that I, CHARLES R. CRANE, 2d, a citizen of the United States, residing at Chicago, in the county of Cook and State of Illinois, have invented a new, original, and ornamental Design for Faucet, of which the following is a specification, reference being had to the accompanying drawing, forming part thereof.

Fig. 1 is a perspective view of a faucet embodying my invention; and Fig. 2 is an end elevation thereof.

I claim:

The ornamental design for a faucet as shown.

CHARLES R. CRANE, 2d.
